UNITED STATES PATENT OFFICE.

MOSES H. DUNN, OF LOS ANGELES, CALIFORNIA.

UNDERREAMER FOR OIL-WELLS.

1,121,907.

Specification of Letters Patent. Patented Dec. 22, 1914.

Application filed December 19, 1913. Serial No. 807,666.

To all whom it may concern:

Be it known that I, MOSES H. DUNN, a citizen of the United States, residing at Los Angeles, county of Los Angeles, and State 5 of California, have invented certain new and useful Improvements in Underreamers for Oil-WellS, of which the following is a specification.

This invention relates to underreamers 10 for oil wells.

My object is to provide a simple, durable and inexpensive underreamer, of few parts, having bits coöperating with each other and with the stock or body of the underreamer 15 in an improved manner; further, to provide a spring coöperating with both of the bits in an improved manner whereby they are spread under substantially equal spring tension and arranged and combined with the 20 stock or body in such manner that the spring is housed and protected without danger of damage thereto.

Having the foregoing, and other, objects in view, the invention consists of those improved features and new combinations of parts set forth fully hereinafter.

In the accompanying drawings: Figure 1 is a side elevation, the bits being retracted; Fig. 2, a similar view with the bits drawn 25 down; Fig. 3, a view taken at right angles to Fig. 2; Fig. 4, an end view of the body, the bits being removed; Fig. 5, an enlarged longitudinal section when the parts are in the condition shown in Fig. 1; Fig. 6, a 30 similar view taken at right angles to Fig. 5; and Fig. 7, an enlarged detail view of the bits detached and in their normal relative positions.

The stock or body 1 is provided with a 40 slot 2 extending therethrough from side to side. The lower end of the slot is preferably closed by the bridge portion 3; but I do not limit myself to the provision of this bridge, as the underreamer will operate satisfactorily without such bridge.

Upwardly undercut hinging abutments 4 are provided on the body and the lower end of the latter has double inclined impact abutments 5, 6, for each of the bits 7.

50 The bits 7 have double inclined contact abutments 8, 9, whose angles substantially conform to the abutments 5, 6. The abutments 5, 6, extend completely across the lower end of the body 1 save where intercepted by the slots 2. The abutments 8, 9, of the bits 7 correspond in length, respec-

tively, to the abutments 5, 6, with which they are adapted to contact. These abutments receive the greater part of the blow or impact transmitted from the bits to the 60 body 1, but a part of said impact is also taken by the hinging abutments 4 with which the upper inclined ends 10 of the bits engage. The shanks 11 of the bits slide in the slots 2 and are provided with longitudinally extending ribs 12 which, by their engagement with the casing of the well, collapse or force the bits toward each other. The ribs are from one to three and one-half 65 inches wide according to the size of the 70 underreamer.

The inner faces of the shanks 11 are provided with elongated eyes 13 which lie side by side within the slots 2 and through these eyes extends a pin or bolt 14 by which the 75 bits are pivotally connected at their upper ends with adaptability to slide up and down in relation to the pin or bolt 14. The pin or bolt 14, in connection with the eyes 13 and the abutments 4 and ends 10, constitutes a 80 pivotal or hinging connection for the bits. The provision of the abutments 4 and ends 10 relieves the pin 14 of a very large amount of shock and strain to which it would otherwise be subjected.

On their inner faces the shanks 11 are provided with lugs 15 having concaved lower faces 16.

A pin or member 17 bridges the slot 2 and around this pin is coiled a spring 18 whose 90 bent ends 19 engage the concaved surfaces 16, whereby the tension of the single spring is exerted on both of the lugs 15 and on both of the bits and draws the bits upwardly, maintaining the abutments 8, 9, in contact 95 with the abutments 6, 5, and the abutments 10 in contact with the abutments 4. The pin 14 is then in the lower ends of the eyes 13. The parts in their retracted condition above described, are adapted for underreaming.

100 Each of the bits is provided with a recess 20 for the reception of a hook, by which the bits may be pulled down against the tension of the spring, when it is desired to insert the tool in the casing. Immediately 105 the tool is inserted in the casing, the ribs 12, by engagement with the walls of the casing, keep the bits pressed toward each other and disposed in their lower position. The pin 14 is then in the upper ends of the eyes 13. 110 When the lower end of the casing is reached, the disengagement of the ribs 12 from the

casing, permits the spring to act which thereupon draws the bits upwardly and forces them outwardly.

The spring, eyes and lugs being contained 5 within the body, are protected from injury. The abutments 5, 6, 8, 9 take the greater part of the impact or blow and relieve the pin 14 therefrom, while the provision of a single pin and spring minimizes the number of 10 parts. The single pin 14, by connecting the bits together, minimizes the danger of loss of one of the bits.

I am aware that modifications of structure could be resorted to in carrying out the 15 invention and I do not, therefore, limit myself to the details herein set forth except where specified in the claims.

Having thus described my invention, what I claim as new and desire to secure by Letters Patent, is:

1. In an underreamer, the combination with a body or stock, of a pair of bits, a common loose or lost motion pivotal connection between the bits and the body, and 25 spring means common to both of the bits adapted for both retracting and spreading them.

2. In an underreamer, the combination with a body, of a pair of pivotally and longitudinally movable bits, and a spring co- 30

operating with both of the bits and adapted to both retract them longitudinally and spread them laterally.

3. In an underreamer, the combination with a body, of a pair of pivotally and longitudinally movable bits, and a single coiled spring whose ends coöperate with the respective bits and are adapted to spread and retract said bits.

4. In an underreamer, the combination with a body, of a pair of pivotally and longitudinally movable bits having shanks provided with internal lugs, a pin carried by the body, and a spring coiled around said pin and having ends coöperating with said 45 lugs and adapted to retract and spread the bits.

5. In an underreamer, the combination with a body, of bits having shanks provided with elongated eyes, a single pin passing 50 through said eyes and connecting them to the body, and a single spring coöperating with the bits and adapted to spread and retract them.

In testimony whereof, I hereunto affix my 55 signature in presence of two witnesses.

MOSES H. DUNN.
